Primary Examiner — Cynthia Ramirez(74) *Attorney, Agent, or Firm* — Quarles & Brady LLP(57) **CLAIM**

The ornamental design for a pallet, as shown and described.

DESCRIPTION

FIG. 1 is a perspective view of a top, front, and left side of an ornamental design for a pallet;

FIG. 2 is a perspective view of a bottom, front, and right side of the pallet of FIG. 1;

FIG. 3 is a top plan view of the pallet of FIG. 1;

FIG. 4 is a right side elevational view of the pallet of FIG. 1, the left side being a mirror image thereof;

FIG. 5 is a front elevational view of the pallet of FIG. 1, the rear being a mirror image thereof; and,

FIG. 6 is a bottom plan view of the pallet of FIG. 1.

The broken lines are included for the purpose of illustrating portions of the pallet which form no part of the claimed design.
